FLUORESCENT LAMP FIXTURE

Simon Gross, 2890 Coacoochee St., Miami, Fla.

Filed May 29, 1959, Ser. No. 56,143

Term of patent 14 years

(Cl. D48—23)

Fig. 1 is a bottom perspective view of a fluorescent lamp fixture, showing my new design.

Fig. 2 is a top perspective view thereof.

Fig. 3 an end elevational view thereof.

Fig. 4 is an enlarged sectional view taken on line 4—4 of Fig. 1.

I claim:

The ornamental design for a fluorescent lamp fixture, as shown.
